UNITED STATES PATENT OFFICE.

GEORGE A. AMSDEN, OF LOWELL, MASSACHUSETTS, ASSIGNOR TO LAMSON CONSOLIDATED STORE SERVICE COMPANY, OF NEWARK, NEW JERSEY, A CORPORATION OF NEW JERSEY.

CONVEYING APPARATUS.

SPECIFICATION forming part of Letters Patent No. 718,185, dated January 13, 1903.

Application filed February 14, 1902. Serial No. 94,019. (No model.)

To all whom it may concern:

Be it known that I, GEORGE A. AMSDEN, of Lowell, in the county of Middlesex and State of Massachusetts, have invented certain new and useful Improvements in Conveying Apparatus, of which the following is a specification.

My invention relates to new and useful improvements in conveying apparatus; and its object is to produce an automatic apparatus in which parcels are automatically picked up and upon reaching their destination are automatically discharged.

My invention consists of certain novel features hereinafter described and particularly pointed out in the claims.

In the accompanying drawings, which illustrate a construction embodying my invention, Figure 1 is a side view of my improved conveying apparatus. Fig. 2 is a top plan view of the same. Fig. 3 is an end elevation of one of the stations. Fig. 4 is a similar view to Fig. 3 with parts in a different position. Fig. 5 is a detail view hereinafter described. Fig. 6 is an end plan view of the support for holding the parcel which is to be detached. Fig. 7 is a detail view showing a parcel grasped by one of the carriers. Fig. 8 is a top plan view of the gripping-clamps. Fig. 9 is a detail view hereinafter explained.

Like letters of reference refer to like parts throughout the several views.

In the upper and lower tracks A and A' there is located and adapted to move the carrier B, to which is secured the casting C, to which is secured the upper clamp D. In the lugs D' is mounted the fixed shaft D², on which is pivotally secured the arm D³, carrying at its lower end the clamp D⁴. The tracks A A' are supported by a suitable wire E and downwardly-extending brackets E'. This bracket supports at its lower end the tracks A² A³, and which form the lower track. On the rear end of the carrier B is the lug E², to which is connected the cable E³, driven by suitable power to move the carriers, of which there may be any number on the line. Supported by said bracket E is a cam-plate F, which at each station is located at different heights, so

that only such carrier as is intended to discharge or pick up at that station is operated by said cam-plate, as those carriers not intended to be operated pass by without being operated. Extending through the cam-plate F is a lever F', pivoted at F² to the track A², and to the rear end of said lever is pivotally secured the link F³, which is connected to the bell-crank lever F⁴, to which is pivotally connected the link F⁵, which in turn is pivotally connected to the rod F⁶, pivoted at F⁷, and on the forward end of said rod F⁶ is a roller F⁸. Contacting with said roller is a latch G, held in its forward position by the spring G' and adapted to engage with the finger G², fast on the rod G³, and to compress the spring G⁴, so that when said latch G is removed from said finger G² the rod G³ is moved upwardly by the spring G⁴. On the upper end of said rod G³ is the support H for a parcel B', Fig. 6. In the construction shown in Figs. 3 and 4 the carrier, as shown, belongs to that station and is to be operated from there to automatically pick up and transmit a parcel B'. In Fig. 3 the carrier is approaching the station previous to its operation, and as it continues its travel the friction-roller D⁶ strikes the lever F' and through the bell-crank lever F⁴, link F⁵, and rod F⁶ the latch G is released from the position shown in Fig. 3 and the support H is raised to the position shown in Fig. 4, with the finger G² against the lug G⁵. As the carrier continues its travel the clamp-jaws D D⁴ open and close on the parcel and transmit it. The shape of the support H permits of the lower clamp coming under the greater part of the load, so that it can be lifted up, together with the bottom jaw D⁴, out of the path of the support H. As shown in Fig. 5, the arm B³ of the carrier passes above the cam-plate F and is not operated at the station shown in Fig. 5 and passes on and is operated in a similar manner to that previously described at the station to which it belongs. As the roller D⁶ does not engage the cam-plate F, Fig. 5, the support H at that station is not raised, so that the carrier passes over the parcel without taking it up. The carrier returning along the upper track with its load passes onto the

lower track, and the arm D³ striking its cam-plate or the one with which it coöperates the clamp-jaws are opened and the parcel drops into a suitable basket J. When it is desired 5 to despatch a parcel, the same is placed upon the support H and the support shoved down so that the finger G² comes under the spring-catch G. This downward movement takes the parcel out of the path of all the carriers 10 except the one which is operated at that station, which, as shown, operates mechanism to raise the parcel in position to be grasped by the open jaws and transmitted. These parcels, which may contain merchandise or 15 cash, are transmitted to the central station, (well known in cable systems,) where they are discharged by the carriers engaging a cam-plate located so as to operate all of the carriers and subsequently are placed in the carriers to which they belong and returned and 20 discharged into their respective baskets, the parcel belonging to the station shown in Figs. 1, 2, 3, and 4 being automatically dropped by the opening of the jaws due to the cam-plate F, and if there should be another parcel at this station it is automatically raised, as previously described, and grasped by the traveling carrier B and carried to the central station. There may be as many of these stations 25 on the line as desired. The cable E³ is continuous and passes around a suitable number of pulleys E⁴, and the way formed by the tracks A A' A² A³ is also continuous.

I do not limit myself to the arrangement 30 and construction shown, as the same may be varied without departing from the spirit of my invention.

Having thus described the nature of my invention and set forth a construction embodying the same, what I claim as new, and desire to secure by Letters Patent of the United States, is—

1. In a conveying apparatus, a track or way, a carrier provided with a clamp adapted to be 45 continuously moved on said track or way, a movable support for the parcel to be carried located out of the path of the traveling clamp, means for holding said support out of the path of the traveling clamp, means for opening said clamp as the carrier approaches said support, mechanism operated by said clamp for releasing said support, and means for lifting said support to raise the parcel into the path of the traveling clamp whereby said parcel is seized by the clamp and conveyed from 50 said support.

2. In a conveying apparatus, a track or way, an endless propelling-cord adapted to be moved continuously along the line of said way, 60 a carrier permanently connected with said cord and movable along said way and having a clamp to seize the parcel to be conveyed, a movable support for the parcel located out of

the path of the traveling clamp, means for holding said support out of the path of the traveling clamp, means for automatically opening said clamp as the carrier approaches said support, mechanism operated by said clamp for releasing said support, and means for lifting said support to raise a parcel into the path 65 of the traveling clamp whereby a parcel is seized by said clamp and conveyed from said support.

3. In a conveying apparatus, a track or way, an endless propelling-cord adapted to be 70 moved continuously along the line of said way and having permanently connected thereto a number of carriers, said carriers having clamps to engage the parcels to be conveyed, a number of movable supports for the parcels, clamp-opening devices adjacent to said supports but located at different positions with relation to the track at the different supports, coöperating clamp-opening portions arranged in different positions on the different 75 clamps whereby a given clamp is opened when passing a given support but not when passing others, means for holding each support out of the path of the traveling clamps, mechanism operated by the clamp engaging its clamp-opening device for releasing said support, and means for lifting said support to raise the parcel into the path of the opened clamp whereby said parcel is seized by said clamp and 80 conveyed from said support. 95

4. In a conveying apparatus, a track or way, an endless propelling-cord adapted to be 90 moved continuously along the line of said way and having permanently connected thereto a number of carriers, said carriers having 100 clamps to engage the parcels to be conveyed, a number of movable supports for the parcels, clamp-opening devices adjacent to said supports but located at different positions with relation to the track at the different supports, coöperating clamp-opening portions arranged in different positions on the different 105 clamps whereby a given clamp is opened when passing a given support but not when passing others, means for holding each support out of the path of the traveling clamps, mechanism operated automatically by the clamp engaging its clamp-opening device for releasing said support, and automatic means for lifting 110 said support to raise the parcel into the path 115 of the opened clamp whereby said parcel is seized by said clamp and conveyed from said support.

In testimony whereof I have signed my name to this specification, in the presence of 120 two subscribing witnesses, this 10th day of January, A. D. 1902.

GEORGE A. AMSDEN.
